(57) **CLAIM**

The ornamental design for a diamond cut, as shown and described.

DESCRIPTION

FIG. 1 is a front elevational view of the diamond cut showing my new design, the right, rear, and left elevational views being identical to the front elevational view;

FIG. 2 is an elevational view rotated about 45° relative to the view of FIG. 1;

FIG. 3 is a top plan view thereof; and,

FIG. 4 is a bottom plan view thereof.

The broken lines are for exemplary illustrative purposes only and form no part of the claimed design.
